CLAIM

The ornamental design for a linear drive, as shown and described.

DESCRIPTION

FIG. 1 is a perspective view of the linear drive of my invention;

FIG. 2 is a front view of the linear drive of my invention;

FIG. 3 is a rear view of the linear drive of my invention;

FIG. 4 is a top view of the linear drive of my invention;

FIG. 5 is a left-hand elevational view of FIG. 2 of the linear drive of my invention;

FIG. 6 is a perspective view of the design showing the right side of the linear drive of my invention; and,

FIG. 7 is a bottom perspective view of the linear drive of my invention.
